CLAIM

I claim the ornamental design for a combined wrist computer or wristwatch and band, as shown and described.

DESCRIPTION

FIG. 1 illustrates a front view of a combined wrist computer or wristwatch and band showing my new design;

FIG. 2 illustrates a perspective view of a combined wrist computer or wristwatch and band showing my new design;

FIG. 3 illustrates a side view of a combined wrist computer or wristwatch and band showing my new design;

FIG. 4 illustrates a rear view of a combined wrist computer or wristwatch and band showing my new design; and,

FIG. 5 illustrates a bottom view of a combined wrist computer or wristwatch and band showing my new design.

The broken lines in FIGS. 1 and 2 are for illustrative purposes only and do not form part of the claimed design.

1 Claim, 5 Drawing Sheets
